CONCEALED ANTENNA MOUNTING

Sidney Ludwig, Cleveland, Ohio, assignor to The Ward Products Corporation, Cleveland, Ohio, a corporation of Ohio

Application March 15, 1941, Serial No. 383,690

14 Claims. (Cl. 250—33)

This invention relates to an automobile radio antenna mounting and, more particularly, to a readily installed mounting which will permit a telescopic antenna to be substantially concealed within the body of an automobile when the antenna is fully telescoped.

Heretofore, telescopic antennas have generally been supported exteriorly of an automobile body. Such exposed mountings generally do not improve the appearance of an automobile and, in the now popular torpedo type of styling, have been rather difficult to install so that the antennas would be in a preferably vertical position unless mountings such as disclosed in my co-pending application No. 314,253 were employed. Efforts have been made to mount antennas interiorly of the automobile bodies so that the telescopic antennas would be substantially concealed within the automobiles when collapsed. Because the slope or curvature of the bodies vary for each model and make of automobile, considerable time and skill was required to secure the antennas within the cowls or fenders of the automobiles so that the antennas will extend out of the automobiles at the desired angle, normally vertical. Also the insulators or stanchions for supporting the antennas adjacent the car body walls had to be ground to shape in each installation to fit the outer surfaces of the car bodies. This was not only a time consuming operation but was also expensive because of the allowance which had to be made for the breakage of insulators being fitted.

It is an object of this invention to provide a concealed antenna mounting which will eliminate the necessity for fitting the insulators and which will permit the antenna to be quickly and readily installed in the cowl or fender of substantially any make or model of automobile so that it may be extended in a vertical or other desired direction.

Other and further objects and advantages of this invention will be apparent from the following specification and drawing. In the drawing, which represents a preferred embodiment of this invention,

Fig. 1 is a side elevation of my antenna mounting showing the mounting extending through a section of an automobile body wall.

Fig. 2 is an enlarged section taken along the line 2—2 of Fig. 1.

Fig. 3 is a section taken along the line 3—3 of Fig. 2, but showing the mounting extending through a section of automobile body wall having a slope different from that shown in Fig. 1.

In the drawing, in which like reference characters refer to like parts, 10 represents a section of car body wall drilled to receive my concealed antenna mounting. It is to be understood that the body wall 10 may constitute any outer wall

of an automobile, such as, for example, the upper cowl wall, fender, or any like portion of an automobile body with an area having a horizontal component. The wall 10 is drilled to 5 provide an opening 11 through which the body of the antenna extends.

The antenna 20 is preferably a rod and tube assembly generally referred to in the art as a telescopic antenna. The outer tube of the antenna 20 is slidably received in a fixed contact ring 22 which carries a plurality of contact shoes 24 which are in constant electrical engagement with the outer tube of the antenna 20 during all extended or retracted positions of the antenna. 15 The fixed contact ring 22 is suitably supported in an insulating sleeve 26, which in turn is carried by a fixed ground sleeve 28.

The ground sleeve 28 is threaded adjacent its upper end to receive an ornamental nut 30 which 20 in turn engages a washer 32 slidable on the threaded portion of the sleeve 28. The washer 32 is provided with a semispherical outer bearing surface which is seated in the top of the hollow stanchion 34. The foot of the stanchion 34 is received in a soft rubber washer pad 36 which 25 engages the outer surfaces of the body wall 10 and spans the opening 11. The hollow stanchion 34 is preferably made of molded Bakelite, or similar plastic material, as shown in Fig. 3 of 30 the drawing, but may be a metal die casting or a similar electrical contacting member, since the antenna 20 is insulated from the sleeve 28, nut 30, and washer 32 by means of the insulator sleeve 26. A lock washer 38 may be interposed 35 between the nut 30 and the washer 32 in order to lock the nut 30 when it is tightened upon the threaded portion of the fixed sleeve 28.

The ground sleeve 28, below its threaded portion, is provided with an antenna cable lead-in spur 40 welded or otherwise secured in electrical contact therewith. The ground sleeve 28 and insulator sleeve 26 are drilled concentrically with the spur 40 to permit a stud 42 to be threaded into the contact ring 22. An insulator 44 insulates the stud 42 from the ground sleeve 28 and spur 40. A standard lead-in cable, comprising an inner antenna lead wire 46, insulating rubber loom 48 and an outer metallic shielding cable 50, is secured by welding or otherwise fastening the lead-in wire 46, stud 42 and the shield 50 to the spur 40.

Below the antenna lead-in spur 40, a shielding tube 52 is force fitted or otherwise secured to the ground sleeve 28. The shielding tube 52 carries a fixed ring 54 on which rests a fastening sleeve 56, concentric with the ground sleeve 28. The upper end of the fastening sleeve 56 is cut off at an angle of approximately 30 degrees, this angle representing about the maximum slope of a car body wall on which the antenna may be mounted,

A slot or other opening 55 is cut adjacent this portion of the fastening sleeve 56 to permit the spur 49 to extend therethrough. A pair of grounding teeth 57 are provided adjacent the uppermost portion of the fastening sleeve 56 to engage the under surface of the wall 10. Opposite the teeth 57, the fastening sleeve 49 is drilled to receive an outwardly extending bolt 58 and the sleeve 56 is cut thereabove to provide an inwardly turned tang 59 which engages the head of the bolt 58 to prevent it from turning. A slotted dog 60 is carried by the bolt 58, the longitudinal slot 61 in the dog 60 permitting the dog to be slid axially with respect to the fastening sleeve 56. The dog 60 is provided with wings 62 turned inwardly with respect to the slotted portion of the dog. In my preferred construction the wings 62 do not engage the fastening sleeve 56, being spaced therefrom when in a vertical position by a spacer 63 carried by the bolt 58. The upper ends of the wings 62 terminate in grounding teeth 64 which engage the under surface of the wall 10. The dog 60 is secured on the bolt 58 by a lock washer 65 and nut 66.

From the foregoing it is apparent that radio-frequency signals picked up by the antenna 20 are conducted from the antenna to the automobile radio set by the contact shoes 24, contact ring 22, stud 42 and the lead-in wire 46. The ground sleeve 28, shielding tube 52, and shielding cable 53 are all electrically connected to each other and to the fastening sleeve 56, which is grounded to the automobile body wall through the grounding teeth 57 and 64. Thus, all conductors of radio-frequency currents between the exposed portions of the antenna 20 and the radio set are shielded within the body of the automobile from motor ignition noise, static charges, and other external interference.

To install my concealed antenna the opening 11 is drilled at the desired location and the nut 30, lock washer 33, semispherical washer 32, stanchion 34 and pad 36 are removed from the assembly. With the dog 60 pushed to its uppermost position and loosely held there by the nut 66, the assembly is inserted upwardly through the opening 11 in the vertical or other direction in which it is desired to have the mounted antenna extend. The grounding teeth 64 will engage the under surface of the wall 10 prior to the teeth 57, but because the dog 60 is loosely held, it will slide downwardly until at least one of the teeth 57 also engage the under surface of the wall 10. If both the teeth 57 do not engage simultaneously, the assembly may be twisted about its axis until both teeth 57 do engage. Because the wings 62 are spaced from the fastening sleeve 56, the dog 60 will cant or tilt if necessary because of the curvature of the wall 10 so that both teeth 64 will be usually maintained in engagement. Thus, there will normally be a four-point engagement with the under surface of the wall 10, since the curvature of the wall 10 is usually so slight with respect to the small area engaged that the curvature is substantially that of a cylindrical surface and not that of an irregular spheroid or similar irregular curved surface. If the wall 10 is so curved, however, that engagement of both teeth 64 with the wall 10 is prevented by a wing 62 engaging the fastening sleeve 56, at least one tooth 64 will be in engagement with the wall 10 and the dog 60 will be tilted so that the engaged tooth 64 will be located substantially above the axis of the bolt 58. The axis of the antenna 20 will then pass through the triangle defined by the

teeth 57 and the engaged tooth 64. Thus, if the wall 10 is so curved that four-point engagement cannot be obtained, at least a stable three-point engagement will be obtained.

With a stable engagement of the grounding teeth 57 and 64 quickly and easily obtained by twisting the assembly about its axis, the assembly is withdrawn and the dog 60 is locked in the selected position by tightening the nut 66 and lock washer 65. The assembly is then reinserted through the opening 11 until the grounding points again engage the undersurface of the wall 10 and the pad 36, stanchion 34, washer 32, lock washer 33, and nut 30 are dropped over the protruding threaded portion of the ground sleeve 28. By tightening the nut 30, the pad 36 will seat on the outer surface of the wall 10 and the stanchion 34 will seat on the pad 36, tilting about the hemispherical surface of the washer 32. After the stanchion 34 has found its most stable position about the washer 32, any gap between the foot of the stanchion 34 and the pad 36, due to the excessive curvature of the wall 10, will be taken up by the resilient pad 36 upon further tightening of the nut 30. Even though there will normally be no gap at the pad 36, it is advisable to tighten the nut 30 as securely as possible to insure that the grounding teeth 57 and 64 bite into the undersurface of the wall 10, thus establishing a good electrical contact and firm mechanical engagement between the fastening sleeve 56 and the wall 10. Because the pressure obtained by tightening the nut 30 is exerted along the axis of the antenna 20, which must necessarily pass through the area defined by the engaged grounding points 57 and 64, a firm and stable concealed mounting of the antenna 20 in the desired position is thus insured.

From the foregoing it is apparent that a concealed antenna mounting may be quickly and readily installed by one service man, first by setting the grounding teeth from within the automobile and then securing the nut 30 from the outside of the automobile. When the antenna is then mounted, the lead-in cable is connected to the radio set and the installation is complete.

The foregoing is a description of the construction and installation of a preferred embodiment of this invention. It is apparent, however, that this embodiment may be modified either in whole or in part. This invention, therefore, is not limited to the specific embodiment disclosed, but only by the appended claims.

What is claimed is:

1. In an antenna mounting permitting substantially the entire antenna to be concealed beneath an external wall of an automobile, a telescopic antenna, a fixed ground sleeve, means for insulating said ground sleeve from said antenna, a nut threaded on said ground sleeve, a washer engaged by said nut, said washer having a spheroidal outer surface, a hollow stanchion seated on said washer, a resilient pad engaged by said stanchion, said pad being adapted to engage the outer surface of the automobile wall and span the opening therein through which the antenna extends, a fastening sleeve connected with said ground sleeve, a pair of fixed grounding teeth on said fastening sleeve, a dog, a pair of grounding teeth on said dog, means for mounting said dog on said fastening sleeve in a slideable and cantable relationship, means for limiting the canting of said dog, and means for locking the relative position of said dog with respect to said sleeve.

2. In an antenna mounting of the class described, a telescopic antenna, a fixed ground sleeve, an adjustable securing means carried by said antenna sleeve, a hollow stanchion, means permitting limited universal movement of said stanchion about the axis of said antenna, a resilient pad engaged between said insulator and the outer surface of an automobile wall, a fastening member mechanically and electrically connected to said ground sleeve, a grounding point on said fastening member, a dog, a grounding point on said dog, and means for mounting and locking said dog on said fastening member in a longitudinally slidable relationship with respect to the axis of said antenna.

3. In an antenna mounting of the class described, an antenna, a fixed sleeve in which said antenna is slidably mounted, adjustable means carried by said sleeve engaging the outer surface of the automobile body wall through which said antenna extends, said means including a resilient portion engaging said automobile wall, and fastening means connected to said sleeve and engaging at a plurality of points the undersurface of the automobile body wall through which said antenna extends, said points of engagement being so located with respect to the axis of said antenna that the points of engagement define an area through which said axis passes.

4. An antenna as defined in claim 3 in which said adjustable means includes a rigid hollow stanchion, means connecting said stanchion to said sleeve to permit limited universal movement of said stanchion with respect to the axis of said antenna, and a resilient pad engaged between said stanchion and the automobile body wall through which said antenna extends.

5. In an antenna as defined in claim 3 in which said adjustable means includes a rigid stanchion, a resilient pad engaged between said stanchion and the automobile wall through which said antenna extends, and means connecting said stanchion to said sleeve comprising a nut threaded on said sleeve, and a washer concentric with said sleeve and having an outer surface spheroidal in shape, said washer being seated on said insulator and permitting said insulator to have a limited universal movement about the axis of said antenna.

6. In an antenna as defined in claim 3 in which fastening means engaging the under surface of the automobile wall through which said antenna extends comprises a fastening member, a first grounding point on said fastening member, a dog movable relatively to said fastening member, a second grounding point on said dog, and means to lock the dog with respect to said fastening member.

7. In an antenna as defined in claim 3 in which said fastening means engaging the under surface of the automobile wall through which said antenna extends comprises a fastening member, a plurality of fixed grounding teeth on said fastening member, a movable grounding tooth connected with said fastening member, and means for locking the movable grounding tooth with respect to said fixed grounding teeth.

8. In an antenna as defined in claim 3 in which said fastening means engaging the under surface of the automobile wall through which said antenna extends comprises a fastening member, a fixed grounding tooth on said fastening member, a dog carried by said fastening member, said dog being slidable and cantable with respect to said

fastening member, a plurality of grounding teeth on said dog, and means for locking said dog with respect to said fastening member.

9. In an antenna as defined in claim 3 in which 5 said fastening means engaging the under surface of the automobile wall through which said antenna extends comprises a fastening device, a plurality of grounding points on said fastening device, a dog carried by said fastening device, said dog being slidable and cantable with respect to said fastening device, a plurality of grounding points on said dog, and means for locking said dog with respect to said fastening member.

10. In an antenna as defined in claim 3 in 15 which said fastening means engaging the under surface of the automobile wall through which said antenna extends comprises a fastening sleeve concentric with said antenna, the upper end of said sleeve adjacent the under surface of the 20 automobile body wall being truncated at an angle to the axis of said antenna, a pair of fixed grounding teeth adjacent the uppermost portion of said sleeve, a bolt carried by said sleeve opposite said fixed grounding tooth, a slotted dog slidable and 25 cantable on said bolt, a pair of grounding teeth on said dog, means for limiting the canting of said dog, and means for locking said dog relatively to said fixed sleeve.

11. In an antenna mounting of the class 30 described, an antenna, a fixed sleeve in which said antenna is slidable, a stanchion, a resilient pad engaged between said stanchion and the upper surface of an automobile wall through which said antenna extends, and means connecting said 35 stanchion and said sleeve and permitting limited universal movement of said stanchion about said antenna sleeve.

12. In an antenna mounting of the class 40 described, an antenna, a hollow stanchion having a substantially truncated conical configuration, a resilient pad engaged between said stanchion and the outer surface of an automobile wall through 45 which said antenna extends, means supporting said antenna in an axially slidable relationship with respect to said stanchion through which said antenna extends, a washer having a semi-spherical outer surface carried by said antenna supporting means, said stanchion having a semi-spherical seat on which said outer surface of said washer is received, thereby permitting limited universal movement of said stanchion about said antenna.

13. In an antenna mounting of the class 55 described, an antenna, means supporting said antenna in an axially slidable relationship, a hollow stanchion through which said antenna extends, and a washer concentric with said antenna, said washer and said stanchion having 60 curved mating surfaces to permit limited angular movement of said stanchion with respect to the axis of said antenna.

14. In an antenna mounting of the class 65 described, an antenna, a fixed sleeve in which said antenna is slidable, a fastening element mechanically connected with but electrically insulated from said antenna, a plurality of grounding points engaging the under surface of the automobile wall through which said antenna extends, one of said grounding points being movable relatively to said fastening element, and means locking said movable grounding point with respect to said fastening element.

SIDNEY LUDWIG.
